UNITED STATES PATENT OFFICE

ROBERT J. STEPHENSON, OF AUBURN, NEW YORK, ASSIGNOR TO STEPHENSON PROTECTAHOOD CORPORATION, OF AUBURN, NEW YORK, A CORPORATION OF NEW YORK

AUTOMOBILE HOOD LINING

Application filed August 26, 1927. Serial No. 215,657.

This invention relates to improvements in linings for automobile hoods.

Heat from the engines of automobiles is radiated through the hood of the automobile and in a comparatively short time destroys or seriously impairs the appearance of the finish on the hood. This is especially true of those automobiles where paint and varnish is used on the hood, a finish of this character quickly losing its luster and quite often cracking.

One object of the invention is to produce a hood lining to prevent the hood being affected as just described, said lining also serving the purpose of deadening noises created by the engine or motor.

A further object is the provision of a lining that will conform to hoods of various contours without causing a fracture or breaking of said lining.

The invention also has as an object a lining more or less impervious to water. By having a lining which absorbs water very slowly, the car or automobile can be washed without danger of the lining being damaged or injured by the water. In the preferred lining the material used can withstand an immersion test for several hours before becoming saturated or soaked.

30 In the accompanying drawings,

Figure 1 is a cross sectional view illustrating more or less diagrammatically an automobile hood having applied thereto a sheet of lining material made in accordance with the present invention.

Fig. 2 is a detail perspective view of a sheet of material embodying the present invention.

Generally stated, the lining constituting the present invention is of sheet-like formation and consists of a sheet of fireproof material 10 and a sheet of sound deadening material 11 mounted on opposite sides of a sheet of material 12 capable of creasing without cracking or breaking. The inter-

mediate sheet 12 is also capable of being immersed in water for several hours without absorbing a very large amount of water or becoming saturated.

More specifically, intermediate sheet 12 is primarily of vegetable fiber, preferably jute fiber, lined on its two sides with paper 13 while the sheet 10 of fireproof characteristics is made of asbestos. The sheet 11, which is a poor conductor of sound is preferably a fairly good grade of felt, usually cotton felt, but in order to retain production at a low cost the felt may be omitted or a paper felt substituted. The use of the felt against the metal hood not only deadens objectionable noises created within the hood but rubbing or movement of the felt surfaces against the metal does not create any noise.

As stated, jute fiber is preferred for the intermediate sheet 12, as it is resilient and pliant and, therefore, capable of being creased or bent to conform to hoods of various contours without breaking or being ruptured. While the lining, or rather sheet 12, is thus capable of readily conforming to the cross sectional contour of the hood to which it is applied, nevertheless, it possesses sufficient rigidity to retain the shape imparted to it without the use of adhesives over its surface. For instance, as shown in Fig. 1, the entire lining for the top sections of the hood lies close to the inner surface of the hood although it is actually attached to the hood only at the meeting edges at the center or top of the hood. In other words, the rigidity of the finished lining is such that it is inherently capable of retaining whatever configuration is imparted to it, dependent on the style or contour of the hood to which it is applied. Likewise, jute fiber absorbs water very slowly so that when the automobile is being washed the lining will take up very little of the water which passes through the louvres in the hood. Other vegetable fibers having these characteristics

may, however, be utilized instead of jute. This feature is also advantageous in that the lining cannot be affected or damaged by the water in the radiator boiling.

6 The asbestos 10 also lends itself readily to different configurations and is an excellent non-conductor of heat. Furthermore, being next toward the motor, danger of fire is eliminated.

10 Taken as a whole, therefore, the present lining would appear to be an ideal one as its use in the interior of the hoods has no tendency to increase objectionable noises but, on the contrary, tends to lessen the same; 15 the asbestos next toward the motor decreases the possibilities of fire and prevents the transfer of heat units in both summer and winter; the asbestos and jute can be creased or shaped to conform to the cross section of hoods without liability of breaking; and 20 the jute prevents injury to the lining by water coming in contact therewith.

What I claim is:

1. An automobile hood lining of sheet-like 25 form consisting of a sheet of double lined jute fiber, said sheet of fiber being resilient and flexible, a covering of asbestos on one side of said sheet of fiber, and a covering of felt on the opposite side of said fiber, said 30 lining being flexible whereby it may readily conform to the shape of a hood and inherently capable of retaining the shape imparted to it when applied to said hood.

2. An automobile hood lining of sheet-like 35 form comprising a sheet of asbestos constituting the motor exposed surface of the lining, a sheet of felt for disposition against the inner surface of the hood, and an intermediate resilient layer of fibrous material having a low coefficient of water absorption and having the capability of substantial flexure without fracture.
